6652X

R. WINANS.

Car Axle.

Patented July 20, 1831

The second edition of the Journal of the Royal Microscopical Society was making, finding of the committee, a good sum and the sum of £1000. The Microscopical Society has been afflicted by financial loss due to the withdrawal of the editor of the Journal and a short time ago.

W. H. Braggs
Prof. D. Jones
Dr. W. H. Braggs

1920-1921

1652 ht

24.
- 11.

(Pentax 28mm 1:2.8)